Primary Examiner — Eric L Goodman*Assistant Examiner* — Vincent T Andrews(74) *Attorney, Agent, or Firm* — Koffsky Schwalb LLC;
Mark I. Koffsky(57) **CLAIM**

The ornamental design of a hand tracking apparatus, as shown and described.

DESCRIPTION

FIG. 1 is a lower front right perspective view of a hand tracking apparatus, in accordance with the present design; FIG. 2 is an upper rear left perspective view thereof; FIG. 3 is a bottom orthographic view thereof; FIG. 4 is a top orthographic view thereof; FIG. 5 is a front orthographic view thereof; FIG. 6 is a left orthographic view thereof; FIG. 7 is a rear orthographic view thereof; and, FIG. 8 is a right orthographic view thereof. The broken lines showing a connector form no part of the claimed design.
